UNITED STATES PATENT OFFICE.

JAMES LOWE PILLING, OF CHICAGO, ILLINOIS, ASSIGNOR TO J. L. PILLING COMPANY, OF CHICAGO, ILLINOIS, A CORPORATION OF ILLINOIS.

REVERSIBLE OSCILLATING ENGINE.

No. 905,747.

Specification of Letters Patent.

Patented Dec. 1, 1908.

Application filed May 6, 1907. Serial No. 372,007.

To all whom it may concern:

Be it known that I, JAMES LOWE PILLING, a citizen of the United States of America, and a resident of Chicago, in the county of 5 Cook and State of Illinois, have invented certain new and useful Improvements in Reversible Oscillating Engines, of which the following is a specification.

This invention relates to reversible oscillating engines, and more especially to the type of oscillating engines set forth in my former patent No. 787,692, dated April 18, 1905, and the present improvement has for its object to provide a simple and efficient 10 structural formation and combination of parts, adapted to afford means for the ready and efficient reversal of the direction of rotation of the engine, all as will hereinafter more fully appear.

20 In the accompanying drawings: Figure 1, is an elevation of the end head of a twin cylinder engine casing, illustrating the ported seats of the same. Fig. 2, is a longitudinal sectional elevation of said engine, illustrating the general arrangement of the engine parts, as well as the ported valve face of one of the engine cylinders. Fig. 3, is a sectional elevation on line $x-x$, Fig. 6, illustrating the reversing valve of the engine. 25 Fig. 4, is a similar view on line $x'-x'$ Fig. 6. Fig. 5, is a vertical transverse section of the engine, on line x^2-x^2 Fig. 4. Fig. 6 is a detail longitudinal section of the engine on line x^4-x^4 Fig. 4. Fig. 7, is a detail elevation 30 of the ported end of the movable member of the reversing valve. Fig. 8, is a detail transverse section of the same intermediate its length. Fig. 9, is a detail elevation of the ported end of the stationary member of the 35 reversing valve.

Similar numerals of reference indicate like parts in the several views.

Referring to the drawings, 1 represents the main inclosing housing having at one 40 end a fixed or integral head 2, and at the other end a removable head 3, to constitute a closed casing in which the cylinders and other moving parts of the engine are contained. As usual in the present type of engines, the fixed head aforesaid carries the bearings for the engine shaft, while the removable head is formed with the series of 45 passages and ports by which air or other motive fluid is conducted to and from the

oscillating cylinders of the engine; and in 55 addition carries the reversing valve by which the direction of revolution of the engine is governed, and to such end said removable head will comprise a construction as follows:—

5 4, is an individual passage or channel formed longitudinally in the head 3, and communicating at each end with a pair of seat ports 6 and 7 of each engine valve, while at its middle said passage 4 is in connection 60 with an individual passage or channel 10 of the reversing valve hereinafter described. 5, is a similar individual passage or channel formed in parallel relation to the channel 4, and communicating at each end with the 65 other pair of seat ports 8 and 9 of each engine valve, while at its middle, said passage 5, is in connection with an individual passage or channel of the reversing valve hereinafter described.

75 12, is a transverse cylindrical bore or chamber formed in the head 3, intermediate of the passages 4 and 5, and adapted to receive a stationary bushing, constituting the stationary member of the reversing valve 80 as hereinafter set forth. Such bore communicates with the aforesaid channels 10 and 11, and also with individual channels 13 and 14, which in turn are in communication with the inlet and the exhaust necks 15 and 16 for the motive fluid, as shown in Figs. 3 and 4.

85 17, is the stationary bushing secured in the aforesaid bore 12, and provided with a marginal flange 18 at its outer end, which 90 fits an outer enlarged portion of the bore 12 to insure the proper position of the bushing in the end head 3 of the engine casing. The said bushing constitutes the stationary member of the manually controlled reversing 95 valve of the engine, and to this end is formed with a closed inner head 19, and with an outer head 20, formed with four equidistantly spaced ports 21, 22, 23 and 24, as shown more particularly in Figs. 5, 100 6 and 9.

105 25, are a corresponding number of longitudinal and radial partitions dividing the interior of the bushing into four passages, which in turn constitute individual connecting channels between the four ports 21, 22, 23 and 24, just described, and the before described channels 10, 11, 12 and 13, through

openings formed in the circular wall of said bushing, and as illustrated in Figs. 3, 4 and 5.

26, is the movable member of the reversing valve above referred to, and which in the present construction is of a cylindrical form adapted to fit and have turning movement in the before described outer enlargement of the bore 12, with the inner end of 10 said valve member in contact with the outer ported end or head 20 of the stationary valve member 17, as illustrated in Figs. 5 and 6. Such movable valve member is formed with an outer closed head and an 15 inner ported head, the ports 27, 28, 29 and 30 of which correspond and are adapted to register with the radial ports 21, 22, 23 and 24 of the stationary valve member.

31, is a central longitudinal partition dividing the interior of the movable valve member into two chambers and with each chamber individual to a pair of the ports 27, 29, and 28, 30 as illustrated more particularly in Fig. 8.

32, is a cover closing the outer end of the aforesaid bore 12, in which the reversing valve is arranged.

33, is a central operating stem on the movable member of the reversing valve; such 30 stem passes through a central orifice in the cover 32, and is formed with a non-circular end for the reception of a suitable handle or crank.

The operation of the reversing valve 35 above described is as follows:—With a partial rotation of the movable valve member in one direction, its ports 28 and 30 are in register with the ports 22 and 24 of the stationary valve member, and motive fluid from the inlet neck 15 is introduced through said ports into the channel or passage 5; at the same time the companion ports 27 and 29 of the movable valve member are in register with the companion ports 21 and 23 of the stationary valve member, to connect the passage or channel 4 with the exhaust neck or passage 16. As so connected the engine is operative in one direction, say to the right. With a partial rotation of the movable 50 valve member in an opposite direction to that above described, the ports 28 and 30 of the movable valve member are brought into register with the ports 23 and 22 of the stationary valve member, and motive fluid from the inlet neck 15 is introduced through said ports into the channel or passage 4; at the same time the ports 27 and 29 of the movable valve member are in register with the ports 24 and 21 of the stationary valve member, to connect the passage or channel 5 with the exhaust neck or passage 16. As so connected the engine is operative in the other direction, say to the left. With the movable valve member turned so that its 65 ports 21, 22, 23 and 24, are out of register

with the ports 27, 28, 29 and 30, of the stationary valve member, motive fluid is cut off from the engine cylinders, and the engine is at rest.

34 is a spring interposed between the 70 cover 32 and the movable member of the reversing valve to yieldingly hold said valve member to its seat.

35 is a central guide stem on the aforesaid movable valve member, and having bearing 75 in a central orifice in the stationary valve member 17 as shown.

36 is a secondary spring interposed between the inner end of the stationary valve member 17 and a removable nut 37 on the 80 inner end of the guide stem 35, to assist in holding the movable valve member to its seat.

38 are counterpart oscillating engine cylinders provided with the usual trunnions 85 39, by means of which they have oscillation in suitable bearings formed therefor in the end heads 2 and 3 of the engine casing, as usual. Such cylinders are provided with the usual pistons and piston rods connected in common to the crank pin of the engine 90 shaft 40.

41 is the usual circular seat on a side of each cylinder, and through which the opposite ports 42 and 43 open. Such ports communicate with the respective ends of a 95 cylinder and are adapted to alternately register with one pair or the other of the before described seat ports 6, 7, 8 and 9, in the normal operation of the engine and in manner usual thereto.

In the present improvement the trunnion 39 at the side of an engine cylinder opposite to the aforesaid circular seat 41 is formed with a piston portion 44, and the bearing therefor with a piston chamber 45, as shown 105 in Fig. 5, and with the area of said piston chamber slightly in excess of the combined area of a pair of the ports 6, 7, 8 and 9.

46 is a pipe or passage extending from a motive fluid inlet portion of the engine, preferably the inlet neck 15, to the piston chamber 45 aforesaid, and adapted to introduce therein a motive fluid pressure in excess of that exerted in the opposite direction through the series of ports 6, 7, 8 and 9, to 110 thus maintain the circular seat 41 of the engine cylinder in proper contact with the valve seat of the engine housing and with a minimum amount of friction and wear, regardless of fluctuations in pressure of the 115 motive fluid supplied to the engine.

47 is a neck on the casing of the reversing valve for the attachment of a suitable lubricator.

Having thus fully described my said invention what I claim as new and desire to secure by Letters Patent is:—

1. A controlling and reversing valve comprising in combination a valve housing forming a part of an end head of the engine cas- 130

- ing and provided with a pair of individual passages adapted for communication with the engine cylinders, crossed partitions in said housing forming four chambers two of which have individual communication with the pair of passages aforesaid, inlet and outlet necks on the valve housing having communication with the other two of said chambers, a circular closed top movable valve member divided by a central transverse partition into a pair of chambers and seated at one end of the four chambers aforesaid, a cover forming a journal for said movable valve member, and means for imparting a turning movement to said valve member, substantially as set forth.
- 5 2. A controlling and reversing valve comprising in combination a valve housing forming a part of an end head of the engine casting and provided with a pair of individual passages adapted for communication with the engine cylinders and having a circular bore, a stationary valve member arranged in said bore and divided radially into four 10 chambers two of which have individual communication with the pair of passages aforesaid, inlet and outlet necks on the valve housing having communication with the other two of said chambers, a circular closed top movable valve member divided by a central transverse partition into a pair of chambers and seated at one end of the four chambers aforesaid, a cover forming a journal for said movable 15 valve member, and means for imparting a turning movement to said valve member, substantially as set forth.
- 15 3. A controlling and reversing valve comprising in combination a valve housing forming a part of an end head of the engine casting and provided with a pair of individual 20 passages adapted for communication with the engine cylinders and having a central bore enlarged at its outer end, a stationary valve member flanged at its outer end and fitted to said bore, said valve member being 25 divided radially into four chambers two of which have individual communication with the pair of passages aforesaid, inlet and outlet necks on the valve housing having communication with the other two of said chambers, a circular closed top movable valve member divided by a central transverse partition into a pair of chambers and seated at one end of the four chambers aforesaid, a cover forming a journal for said movable 30 valve member, and means for imparting a turning movement to said valve member, substantially as set forth.
- 30

Signed at Chicago, Illinois this 30th day of April 1907.

JAMES LOWE PILLING.
